(57) **CLAIM**

The ornamental design for pocket field tool bit, as shown and described.

DESCRIPTION

FIG. 1 is perspective of the pocket field tool bit;
FIG. 2 is a front view of the pocket field tool bit;
FIG. 3 is a left side view of the pocket field tool bit;
FIG. 4 is a back view of the pocket field tool bit;
FIG. 5 is a right side view of the pocket field tool bit;
FIG. 6 is a top view of the pocket field tool bit; and,
FIG. 7 is a bottom view of the pocket field tool bit.
The broken lines depict portions of the pocket field tool bit in
which the design is embodied that are not considered part of
the claimed design.
